SOOT BLOWER

Norman L. Snow, New Canaan, Conn., and Willis P. Thomas, Highland Park, Harry E. Brelsford, Birmingham, and Curtis L. Howse and Frank Bowers, Detroit, Mich., assignors to Diamond Power Specialty Corporation, Detroit, Mich., a corporation of Michigan

Application December 27, 1932, Serial No. 649,107
Renewed November 22, 1937

11 Claims. (Cl. 122—392)

This invention relates to a fluid heater cleaner of the character in which a blower element is adapted to discharge cleaning fluid adjacent parts of the fluid heater to be cleaned.

5 One of the primary objects of this invention is to provide a cleaner of the above mentioned character which will include a movable blower element and to provide an improved means for effecting the desired movement of the blower element.

10 The invention further contemplates the provision of power driven means for effecting an oscillation or like movement of a blower element to the end that the cleaning fluid discharged from the blower element will be properly directed adjacent the portions of the fluid heater to be cleaned.

15 Numerous other objects and advantages of this invention will become more apparent as the following description proceeds, particularly when reference is had to the accompanying drawings, wherein:

20 Fig. 1 is a side elevational view partly in section of a fluid heater cleaner constructed in accordance with the teachings of this invention;

25 Fig. 2 is a semi-diagrammatic view partly in section and partly in elevation showing details of the blower element actuating means;

30 Fig. 3 is a sectional view through the motor forming a part of the structure shown in Fig. 2.

35 Referring then particularly to the drawings wherein like reference characters designate corresponding parts throughout all views, the numeral 10 designates the wall of a fluid heater which, it is to be understood, may be an air heater, boiler or any similar apparatus. Mounted in an opening 11 in this wall is a wall box 12 through which a blower element 13 extends. The blower element is adapted to be supplied with cleaning 40 fluid in a manner which will be later described and is provided with nozzles for discharging this cleaning fluid adjacent the portions of the fluid heater to be cleaned, one of the nozzles being illustrated in Fig. 1 of the drawings and being 45 designated by the reference character 14.

Exteriorly of the fluid heater the blower element is journaled in a cleaning fluid supply pipe 105. This supply pipe will be connected to any suitable source of cleaning fluid which may be 50 air under pressure, steam, or any other desired fluid or substance. It is a feature of the invention that the blower element may be oscillated and means are provided for automatically terminating the oscillation of the blower element after 55 a predetermined desired oscillation thereof.

For oscillating the blower element there is directly secured to the same the rotor 80 of a fluid motor designated generally by the reference character 81. The rotor is disposed centrally of a housing 82 providing an annular chamber 83 between the rotor and the inner surface of the housing. A vane or projection 84 secured to the rotor spans the annular chamber 83 and wipes the inner surface of the housing as the rotor is oscillated.

5 Closing the space between the rotor and the housing at one side of the rotor is a plate or member 85 which may conveniently be formed on the inner wall of the housing as illustrated. Tapped into the housing to communicate with the chamber 83 on opposite sides of member 85 are conduits 86 and 87 whereby fluid under pressure may be admitted to the annular chamber to act on opposite sides of the vane 84. Restricted orifices are preferably formed in the conduits 86 and 87 20 for a purpose which will hereinafter be more fully described.

25 The conduits 86 and 87 are tapped into chambers 90 and 91, respectively, these chambers containing a liquid which is utilized to act on the vane 84 to drive the rotor 80. By utilizing a liquid as the propelling force for the rotor, the orifices 88 may be conveniently utilized for retarding and regulating the speed of movement of the rotor as desired.

30 To cause the liquid in chambers 90 and 91 to be supplied to the chamber 83, provision is made to admit fluid under pressure to the upper ends of the chambers 90 and 91. The means for accomplishing this comprises a valve housing 92 providing a chamber 93 into which conduits 94 and 95 are tapped, the conduits communicating with the upper ends of cylinders 90 and 91, respectively. Exhaust conduits 96 and 97 are also tapped into the chamber 93, these exhaust conduits leading 40 to any suitable point of exhaust (not shown).

35 Disposed within chamber 93 are spaced pistons 98, these pistons being mounted on a rod 99 which projects through the ends of valve casing 92 and which is secured to a yoke 100. This 45 yoke is mounted for reciprocation in suitable guide bearings 101 and is provided with a lug or projection 102 adapted to be periodically engaged by an arm 103 suitably fixed for rotation with the rotor 80.

50 The numeral 105 designates the cleaning fluid supply pipe, and tapped into this conduit is a conduit 106 which extends into the valve casing 92 and communicates with the chamber 93 substantially centrally thereof. A valve 107 disposed 55

in the conduit 106 controls the flow of fluid under pressure from the supply pipe 105 to the chamber 93.

Communicating with the conduit 106 beyond the valve 107 therein is a conduit 108 which communicates with the lower end of a cylinder 109. Disposed in this cylinder is a piston 110, and connected to this piston is the stem 111 of a valve 112 which controls the flow of cleaning fluid through the supply pipe 105 to the blower element 13. A spring 114 acts on the upper face of piston 110 to normally hold the valve 112 closed. It will be noted that the conduit 106 is tapped into the supply pipe in advance of valve 112 so that whenever valve 107 is opened, fluid under pressure will be supplied to the valve chamber 93 and to the cylinder 109.

The valve 107 is normally held closed by a spring 115 which surrounds the stem 116 of this valve and engages a collar 117 on this stem. For moving valve 107 to open position against the force exerted by spring 115, there is provided a cam 118 fixed to a shaft 119 for rotation with the same. Also fixed to shaft 119 for rotation with the cam 118 is a ratchet wheel 120 having ratchet teeth 121 adapted to be engaged by a pawl 122 pivotally connected to one end of the yoke 100. It will thus be apparent that a reciprocation of the yoke 100 will effect a step by step 30 rotative movement of the ratchet wheel 120 and thus of the cam 118. Rotatably journaled on shaft 119 is a sheave wheel 125, and pivotally secured to this sheave wheel is a pawl 126 adapted to engage in an enlarged recess or tooth 127 formed in the periphery of the ratchet wheel 120. A chain or like flexible element is trained around the sheave wheel 125 and has depending ends 128 and 129 by which the sheave wheel may be rotated. The depending end 129 of the chain 40 passes through a suitable stationary guide 130 against which a collar 131 fixed to the end 129 of the chain is adapted to abut to limit movement of the flexible chain in one direction.

In operation, it will be understood that when the blower element is not operating, the cam 118 will be so positioned rotatively with reference to valve stem 116 that valve 107 will be closed. With valve 107 closed, no fluid under pressure will be admitted to chamber 93, and valve 112 which controls the admission of cleaning fluid to the blower element, will be closed by spring 114 acting on piston 110.

To initiate the operation of the blower element, the end 129 of the flexible actuating element will be pulled downwardly to rotate sheave wheel 125 in a clockwise direction. This rotation of the sheave wheel will be continued until the pawl 126 engages in the notch 127 of the ratchet wheel 120, it being understood that during this clockwise rotation of the sheave wheel, the ratchet wheel will remain stationary. As soon as the pawl 126 engages in the notch 127, the end 128 of the flexible element may then be pulled to rotate the sheave wheel in a counter-clockwise direction. By virtue of the engagement of pawl 126 in notch 127, the ratchet wheel will rotate with the sheave wheel during this counter-clockwise rotation of the latter. The counter-clockwise rotation of the sheave wheel is continued 60 until the collar 131 engages the stop 130.

The counter-clockwise rotation of the sheave wheel and ratchet wheel causes the cam 118 to be rotated to a position where it engages valve stem 116 and opens valve 107. Opening of this 75 valve admits fluid under pressure to the valve

chamber 93 and to conduit 108, the fluid under pressure in this latter conduit entering cylinder 109 beneath piston 110. This forces the piston upwardly against the force exerted by spring 114, thus opening valve 112 and admitting cleaning fluid under pressure to the blower element 13. 5

Admission of fluid under pressure to chamber 93 provides for the supplying of fluid under pressure to the top of one or the other of the chambers 90 and 91, depending upon the positions of 10 pistons 98. In the position of the parts shown, chamber 90 is connected to the exhaust conduit 96 by way of conduit 94 and a portion of chamber 93, while fluid under pressure is admitted to chamber 91 by way of its conduit 95 which communicates with the portion of the chamber 93 to which the fluid under pressure is being supplied. Fluid under pressure acting on the top of the liquid in chamber 91 will force the liquid from this chamber through conduit 87, causing 20 the liquid to act on vane 84, thus rotating the rotor in a clockwise direction.

Just before the rotor has rotated sufficiently to bring the vane thereon into contact with member 85, arm 103 will engage lug 102 to shift the 25 yoke 100 and the pistons 98 to the left. This shifting of the pistons will cause fluid under pressure to be supplied to chamber 90 and will connect chamber 91 to the exhaust so that the rotor will then be rotated in a counter-clockwise 30 direction. As previously mentioned, the orifices 88 provide a convenient means for controlling the speed of oscillation of the rotor 80.

Each time the yoke is reciprocated, the pawl 122 which it carries will ratchet the wheel 120 35 in a counter-clockwise direction. It will be obvious that after a predetermined movement of the ratchet wheel in this direction, the cam 118 will be moved out of engagement with the stem 116 of the valve 107, thus permitting this valve to 40 close and thus terminating the operation of the fluid motor 81 and cutting off the supply of cleaning fluid to the blower element.

It will be apparent that the extent of travel which must be imparted to the cam to move the 45 same out of engagement with the valve stem 116 will determine the number of oscillatory movements which will be imparted to the blower element before valve 107 is closed. Thus, by properly positioning the cam 118 with reference to 50 ratchet wheel 120 and by properly locating collar 131 on the flexible actuating chain, a desired initial rotative positioning of the cam upon actuation of the actuating chain may be effected. Obviously, the initial positioning of the cam will 55 predetermine the extent of movement of the cam necessary to move the same out of engagement with the valve stem to thus allow a closing of the valve 107.

From the above it will be apparent that the 60 invention provides a fluid heater cleaner which includes a blower element mounted for oscillation and which includes improved power driven means for effecting an oscillation of the blower element. In the embodiment of the invention 65 which is illustrated, the oscillation of the blower element may be initiated, and means is provided for automatically terminating the operation of the blower element after the same has been operated through a predetermined number of 70 cycles.

While the invention has been described with some detail, it is to be understood that the description is for the purposes of illustration only and is not definitive of the limits of the inventive 75

idea. The right is reserved to make such changes in the details of construction and arrangement of parts as will fall within the purview of the attached claims.

5. What we claim as our invention is:

1. In a fluid heater cleaner, a blower element mounted for oscillation, means connected to said blower element for oscillating the same, and means controlled by said blower element oscillating means for automatically terminating the oscillation of said blower element after a predetermined plural number of cycles of oscillatory movements thereof, each cycle consisting of a movement away from a starting point and a return movement in a reverse direction to said starting point.

2. In a fluid heater cleaner, a blower element mounted for oscillation, power driven means connected to said blower element for oscillating the same, and means actuated by said power driven means for automatically terminating the oscillation of said blower element after a predetermined plural number of cycles of oscillatory movements thereof, each cycle consisting of a movement away from a starting point and a return movement in a reverse direction to said starting point.

3. In a fluid heater cleaner, a blower element mounted for oscillation, a fluid motor connected to the blower element for oscillating said blower element, means for admitting fluid under pressure to said fluid motor to actuate the same, and means actuated by said fluid motor for cutting off the supply of fluid under pressure to said fluid motor after the same has imparted a predetermined plural number of cycles of oscillatory movements to said blower element, each cycle consisting of a movement away from a starting point and a return movement in a reverse direction to said starting point.

4. In a fluid heater cleaner, a movable blower element, means for supplying cleaning fluid to said blower element, means connected to said blower element for moving said blower element through a plurality of cycles of movement, and means actuated by said blower element moving means automatically acting to cut off the supply of cleaning fluid to the blower element and to terminate the actuation of said moving means after a predetermined plural number of cycles of oscillatory movements of the blower element, each cycle consisting of a movement away from a starting point and a return movement in a reverse direction to said starting point.

5. In a fluid heater cleaner, a blower element mounted for oscillation, an oscillatory fluid motor connected to said blower element for oscillating said blower element, a cleaning fluid supply line for said fluid motor, valve means in said supply line for controlling the admission of fluid under pressure to said fluid motor, means for admitting fluid under pressure to said valve means, and means actuated by said valve means for automatically cutting off the supply of fluid under pressure to said valve means after a predetermined oscillation of the blower element.

6. In a fluid heater cleaner, a blower element mounted for oscillation, a rotor fixed to said blower element and having a vane projecting radially from the same, valve means for causing fluid under pressure to act alternately on opposite sides of said vane to effect an oscillation of said rotor, a second valve for controlling the admission of fluid under pressure to said valve means, means constantly acting to close said sec-

ond valve, a cam so constructed and positioned that when the same is actuated it opens said second valve and holds the same open, and means actuated by said valve means for moving said cam to a position where said valve closing means closes said second valve after a predetermined oscillation of said blower element. 5

7. In a fluid heater cleaner, a blower element mounted for oscillation, a fluid motor connected to said blower element for oscillating said blower element, a double acting reciprocating valve controlling the admission of fluid under pressure to said fluid motor, a second valve for controlling the admission of fluid under pressure to said double acting valve, a cam adapted to open said second valve, means for closing said second valve and means actuated by the reciprocation of said double acting valve for moving said cam to a position where said valve closing means closes said second valve after a plural number of reciprocatory movements of said reciprocating valve. 10

8. In a fluid heater cleaner, a blower element mounted for oscillation, means for supplying cleaning fluid to said blower element, a fluid motor operated by the pressure of the cleaning fluid 15 and connected to said element to oscillate the same, means for supplying cleaning fluid to said motor, and means actuated by the fluid motor operable to cut off the supply of cleaning fluid to the said blower element and to the said motor 20 after a predetermined plural number of cycles of oscillatory movements of said blower element, each cycle consisting of a movement away from a starting point and a return movement in a reverse direction to said starting point. 25

9. In a fluid heater cleaner, a blower element mounted for oscillation, a fluid motor operated by the pressure of the cleaning fluid and connected to said blower element to oscillate the same, means controlling the supply of cleaning fluid to 30 said blower element and to said fluid motor, and means actuated by said fluid motor and acting on said control means to cut off the supply of cleaning fluid to said blower element and to said fluid motor after a predetermined plural number 35 of cycles of oscillating movements of said blower element, each cycle consisting of a movement away from a starting point and a return movement in a reverse direction to said starting point. 40

10. In a fluid heater cleaner, a blower element mounted for oscillation, a fluid motor connected to said blower element for oscillating the same, a cleaning fluid supply line for the blower element, a valve in said line for controlling the admission of cleaning fluid to the blower element, means operable to effect an opening of said valve and to admit fluid under pressure to said fluid motor for actuating the latter, means for actuating said last mentioned means to initiate the 45 actuation of said motor and to effect an opening of said cleaning fluid supply valve, and means controlled by said fluid motor for actuating said means which admits fluid under pressure to the motor and which effects the actuation of said 50 valve to cause the same to cut off the supply of fluid under pressure to the motor and to effect a closing of the cleaning fluid supply valve after a predetermined plural number of cycles of oscillatory movements of the blower element, each 55 cycle consisting of a movement away from a starting point and a return movement in a reverse direction to said starting point. 60

11. In a fluid heater cleaner, a blower element mounted for oscillation, a rotor fixed to said 65

70

75

blower element, a housing for said rotor cooperating with the same to form an annular chamber, a vane on said rotor spanning said chamber, a pair of liquid containing chambers, connections between said liquid containing chambers and said annular chamber, regulable restrictions in said connections, a supply of fluid under pressure, means for controlling the admission of fluid under pressure to said liquid containing chambers, a valve for controlling the admission of fluid under pressure to said last mentioned means, a cleaning fluid supply line for the blower element, a valve in said supply line controlling the

admission of cleaning fluid to the blower element, means operating upon actuation of said first mentioned valve to effect an actuation of said cleaning fluid supply valve, means for opening said first mentioned valve and for holding the same open, and means operating to release said holding means after a predetermined oscillation of the blower element.
